UNITED STATES PATENT OFFICE.

NORMAN BENJAMIN RANDALL, OF PHILADELPHIA, PENNSYLVANIA.

GAS-ENGINE.

SPECIFICATION forming part of Letters Patent No. 355,101, dated December 28, 1886.

Application filed June 3, 1886. Serial No. 204,030. (No model.)

To all whom it may concern:

Be it known that I, NORMAN BENJAMIN RANDALL, of Philadelphia, in the county of Philadelphia and the State of Pennsylvania, have invented new and useful Improvements 5 in Gas-Engines, of which the following is a specification, reference being had to the annexed drawings, forming a part thereof, in which—

10 Figure 1 is a side elevation of my improved gas-engine. Fig. 2 is a plan view. Fig. 3 is a vertical longitudinal section. Fig. 4 is a transverse section taken on line $x-x$ in Fig. 3. Fig. 5 is a longitudinal section of one end of 15 the gas-compressor. Fig. 6 is a side elevation of the front head of the air-compressor. Fig. 7 is a detail sectional view of one of the air-valves of the air-compressor.

Similar letters of reference indicate corresponding parts in the different figures of the drawings.

My invention relates to the class of gas-engines in which the power is generated in the power-cylinder by the explosion of air and 25 gas under compression; and the object of my invention is to utilize the heat which is commonly wasted in gas-engines for expanding the air supplied to the power-cylinder.

The invention consists of the combinations 30 of parts, including their construction, substantially as hereinafter set forth, and pointed out in the claims.

The piston-rod guide A, supported by the base B, is provided with a flange, C, to which 35 is secured the air-jacket D of the power-cylinder E. The air-jacket D is preferably cast integrally with the power-cylinder E. The air-jacket D is provided with a removable head, a, and the power-cylinder E is provided 40 with a removable head, b. To the power-cylinder E is fitted the piston F, which is secured to the piston-rod G, extending through the sleeve c, connecting the front heads of the air-jacket and power-cylinder, and through the 45 gland d, of the usual form, on the head of the air-jacket. The piston-rod G is connected with the cross-head H, received in the guide A. In the cylinder-head I, attached to or formed on the base B, is secured the air-compressor cylinder J, axially in line with the power-cylinder E. The air-compressor cylinder J is provided 50 with a piston, K, to which is attached

a piston-rod, L, extending through a gland, e, on the head I. A series of valve apertures, f, are formed in the head I, around the gland 55 e, and provided with valves g, fitted to seats on the inner surface of the head and surrounding the apertures f. The valves g are supported by spindles h, extending through guides i, secured to the cylinder-head. The spindles 60 h are threaded at their outer ends, and provided with nuts j, between which and the guides i are placed spiral springs k, surrounding the spindles and tending to hold the valves to their seats.

The opposite or back end of the cylinder is provided with one or more valves, g, opening into the cylinder, and mounted in the same manner as the valves at the front end of the cylinder. The cylinder J is provided with 70 ports l l', leading to the valve-chambers m m', in which are placed the valves n n'.

The valve-chambers above the valve-seats communicate with each other and with the pipe M, which leads to and communicates with 75 the air-jacket D of the power-cylinder. The piston-rod L is connected by an offset rod, N, with the cross-head H, so that the pistons of the power-cylinder and the compressor-cylinder move together. The cross-head H is connected by means of a connecting-rod, O, with a crank, P, on the crank-shaft Q, journaled in boxes o, supported by the base B.

To the shaft Q is secured a fly-wheel, R, which serves to equalize the motion of the engine in the usual way.

In the lower side of the power-cylinder E are formed ports p p', communicating with the valve-chambers q q', formed in a body of metal connecting the power-cylinder and air-jacket 90 at their lower sides. The valve chambers q q' communicate through an exhaust-passage, r, with the exhaust-pipes s. Air-supply ports t t' communicate between the air-space of the jacket D and the valve-chambers q q'. In the 95 lower sides of the valve-chambers q q' are formed ignition-ports u u', through which the explosive charge in the cylinder is ignited by the continuously-burning gas-jets v v'. Pipes w, communicating with the gas-supply pipes 100 of the gas-jets v v', lead to the valve-chambers q q', to supply the ignition-chambers with a small quantity of gas.

In the valve-chambers q q' are placed the os-

cillating valves y y' , which are chambered on diametrically-opposite sides, and are provided with a small transverse aperture, z , for igniting the charge in the cylinder. The valves y y' are 5 provided with spindles a a'' , to which are secured arms b b'' , which extend upward and are received in grooved cams c c'' , secured to the lay-shaft S , journaled in bearings secured to the side of the air-jacket D , and to the 10 guides A . On the end of the lay-shaft S nearest the crank-shaft Q is secured a miter-wheel, d' , which takes motion from a similar wheel, d'' , on the crank-shaft Q . The cams c c'' are arranged relative to the movement of 15 the piston F , so that the valves y y' will admit air from the jacket D to the power-cylinder, igniting the combustible mixture at the proper time in the stroke of the power-piston F , and open at the end of the stroke of the power-pis- 20 ton to allow the products of combustion to escape through the exhaust-passage r and the exhaust pipe s .

The air-ports t t' are provided with valves e e'' , whose spindles f f'' are provided with the 25 arms g g'' , which are pivotally connected with the adjusting-rod h' . The rod h' is screw-threaded and passes through a nut, i' , secured to the air-jacket D . The pivotal connections of the arms g g'' with the rod h' are swiveled, 30 so as to permit of turning the rod h' , when desirable, to simultaneously adjust both of the valves e e'' .

Below the air-jacket D is suspended a gas-compressor cylinder, T , containing a piston, 35 j' , carried by the piston-rod k' , which extends through a gland in the forward end of the compressor T . Opposite ends of the gas-compressor cylinder T are provided with valve-casings U , each containing a suction-valve, l'' , 40 and a discharge-valve, m'' . The lower or supply ends of the valve-casings are connected by the pipe V , which communicates with a gas-supply pipe, W , provided with a governor-valve, X . The upper or discharge ends of the 45 valve-casings U are connected directly with opposite ends of the power-cylinder.

The piston-rod k' passes through a guide, n'' , formed in the side of the base B , and is connected by a link, o' , with the longer arm 50 of the angled lever p'' , the shorter arm of the angled lever p'' being connected by a rod, q'' , with the eccentric-strap r' , surrounding an eccentric, s' , on the crank-shaft Q . The spindle t'' of the governor X is connected with the 55 governor A' , which receives motion through spiral gearing from the lay-shaft S . Gas having been admitted to the supply-pipe W , and the igniting-jets v v' having been lighted, the engine is revolved by means of the fly-wheel, 60 thus drawing in air through the valves of the air-compressor, and forcing it through the pipe M into the air-jacket D . At the same time the gas-compressor T takes charges of gas from the supply-pipe, and forces them alter- 65 nately into opposite ends of the power-cylinder. As soon as the back end of the power-cylinder has received the charge of explosive

mixture behind the power-piston F , the ignition-aperture z of the valve y being charged with a combustible mixture of gas and air, and 70 the charge having been lighted by the igniting-burner and shut off from the external air by the turning of the valve, fire is communicated to the charge contained in the cylinder by the burning gas in the cavity in the valve. 75 The piston F is pushed forward by the pressure generated by the explosion of the mixture, imparting motion to the crank-shaft Q , also to the piston of the air-compressor J . Upon the opposite side of the piston the space in the 80 power-cylinder E is filled with the products of combustion resulting from the charge previously exploded in that end of the cylinder, and the valve y' is turned by the mechanism already described, so as to establish communication between the port p' and the exhaust-passage r , allowing the products of combustion to escape through the port, exhaust-passage, and the exhaust-pipe s . When the stroke 85 in that direction is completed and the momentum of the fly-wheel starts the piston in the opposite direction, the valve y' is turned so as to establish communication between the air-port t' and the port p' , to admit air from the air-jacket D to the power-cylinder. At 90 the same time the gas-compressor T , having previously taken the charge of gas from the supply-pipe W , quickly forces a volume of gas into the power-cylinder, which mixes with the air and is exploded in the manner already described in connection with the opposite end of the cylinder. As this operation is repeated the piston K of the air-compressor draws the air alternately from opposite ends of the cylinder and forces it through the ports l l' , the 95 valve-chambers m m' , and pipe M to the jacket D , the charge thus forced into the jacket being retained by the check-valves h h' . The air in the jacket D is subject to compression and to expansion by the heat of the power-cylinder E , enlarging its volume and increasing its pressure, thus utilizing the heat of the power-cylinder, which is commonly carried off by water employed in keeping down the temperature of the cylinder, and therefore lost. 100

Besides economizing the heat and reducing the temperature of the power-cylinder, I am enabled to maintain the power-cylinder at such a temperature as will prevent the burning of the oil used in lubrication, and also prevent 105 the condensation of the steam generated by the explosion of the gaseous mixture.

Having thus described my invention, what I claim as new, and desire to secure by Letters Patent, is—

1. The combination, with the power-cylinder E and air-jacket D , surrounding the power-cylinder, of valves for admitting air from the air-jacket to opposite ends of the power-cylinder in alternation, the gas-compressor T , forcing gas under pressure into opposite ends of the power-cylinder in alternation, and means, substantially as herein shown and described, for igniting the explosive charge contained by 110

the power-cylinder and releasing the products of combustion.

2. The combination of the power-cylinder E, provided with the piston F, the air-jacket 5 D, surrounding the power-cylinder, the valves y y', provided with spindles a' a'' and arms b' b'', the cams c' c'', the lay-shaft S, carrying the cams and receiving motion from the crank-shaft, the gas-compressor T, link o', angled 10 lever p'', connecting-rod q'', eccentric-strap r',

and eccentric s', the air-compressor J, provided with the piston K, and valves g h'' h³, the igniting-ports u u', and the mechanism connecting the moving parts of the engine, substantially as herein shown and described.
